UNITED STATES PATENT OFFICE

148,711

DESIGN FOR A CIGARETTE PACKAGE HOLDER

Alfred P. Leiserowitz, Des Moines, Iowa

Application March 15, 1946, Serial No. 127,538

Term of patent 3½ years

(Cl. D85—2)

To all whom it may concern:

Be it known that I, Alfred P. Leiserowitz, a citizen of the United States, residing at Des Moines, in the county of Polk and State of Iowa, have invented a new, original, and ornamental Design for a Cigarette Package Holder, of which the following is a specification, reference being had to the accompanying drawing, forming part thereof.

The characteristic feature of my design resides in the combination on the cigarette package holder disclosed of the specific cut-outs at the top and the specific cut out portions on the bottom, all as shown.

I claim:

The ornamental design for a cigarette package holder, substantially as shown and described.

ALFRED P. LEISEROWITZ.
